ALARM-CIRCUIT SYSTEM

Application filed January 25, 1928, Serial No. 249,355, and in Germany July 3, 1926.

Our invention relates to an alarm circuit system, in which the alarm calls of alarming stations received in alarm receiving stations are sent on to other alarm receiving stations. 5
In alarm installations in which the alarm calls received are to be collected in a central station and sent on from the latter to further alarm receiving stations (district stations), it is desirable that the said district-stations 10 which are allotted to the single groups of alarm giving stations, should be notified as early as possible of any incoming alarm within their district. The object of the present invention is to accomplish such result in a 15 simple and reliable manner, this being achieved by providing arrangements in the central station for giving a preliminary alarm in district stations, before the alarm calls are transmitted.

20 A construction according to the present invention is illustrated by way of example in the accompanying drawing. In the drawing is shown an alarm giving station AGSt 431 with the telephone instrument N, a distributing station VSt 1, the alarm receiving station HBW with the switch devices required for explaining the invention, and two further alarm receiving stations FW1 and FW2. The selector W1 shown in the drawing 25 with the switch arms w11, w12, w13 and w14 is a rotary selector of the well known type shown in United States Patent No. 1,126,727. The selector W2 with the two switch arms w21 and w22 shown, is a lifting rotary selector 30 of the well known construction. Its corresponding advance magnets are the lifting magnet H and the rotary magnet D2. The rotary magnet D1 is the advance magnet for the selector W1.

35 Let it be assumed that an alarm is to be given from the alarm giving station AGSt 431 to the alarm receiving station HBW. From the latter the alarm is then sent on to the further alarm receiving stations FW1 and FW2 in a manner which is immaterial to the present invention. The alarm may be sent from the central alarm receiving station HBW to the district receiving station FW1 or FW2, in the manner described in our 40 British Patent Number 270,755. The sig-

nals may also be transmitted manually, as for example by means of a key ST 11 in the central station and a bell ST 12 located in the district receiving station FW1 as shown in the drawing. In the alarm giving 55 station AGSt 431 are provided devices as described in our British Patent No. 269,941 and not shown in the drawing, by means of which is obtained the characterizations of the alarm giving station at the alarm receiving station HBW. 60

The alarm giving station AGSt 431 is connected by means of a connection line to the distributing station VSt 1 in which by means of call seekers, as shown in the above mentioned British Patent No. 269,941, the connection to the alarm receiving station is effected in a well known manner. The relay A arranged at the distributing station VSt 1, is used as a current impulse relay for the 70 current impulses sent from the alarm giving station AGSt 431. The relay B is intended for switching processes which are not shown in the drawing and are immaterial to the invention. These processes are explained in 75 detail in our British Patent No. 269,941. With the aid of its contact 1a, the current impulse relay A effects the sending on of the current impulses received, to the alarm receiving station HBW. 80

The characterization of the alarm giving station AGSt 431 in the alarm receiving station HBW when an alarm, for instance a fire alarm, is sent from the latter station, is obtained owing to the fact that at the said 85 alarm giving station is dialed a given number, in our example, the No. 431, for instance by means of a number disc (not shown in the drawing), and this number is indicated to the attendant in the alarm receiving station 90 by the lighting of lamps. The call seeker AS in the connection line a b is set then to the said alarm giving station. Owing to this setting, through the c conductor of the call seeker is closed the following test circuit:—earth, c arm of the call seeker, c conductor, windings I and II of the test relay P, rest contact 3f, battery, earth. On the relay P becoming operative, the winding II of the 95 relay will be short circuited by the contact 100

2p for this purpose. If during the period an alarm is sent on over this connection line, another alarm happens to be given by a second alarming station of the same district, 5 one of the other idle call-seekers multiplied with the first one, will be set in motion. But at the moment this one reaches the line connecting the first alarming station with the distributing station VSt, its test relay cannot 10 be excited, the high-ohmic winding of the same being connected in parallel to the low-ohmic winding I of the test relay P. The relay of the second call-seeker does not get sufficient current to become operative and 15 therefore does not stop the call seeker at such moment, preventing in this manner the connection of the second connection line through to the line of the first alarming station. Owing to the operation of the relay P, the contact 20 5p will be opened, and the release magnet M of the selector W2 switched off. Owing to the closing of the contact 12p, a circuit will be closed for the call lamp L II:—earth, working contact 12p, lamp L II, battery, 25 earth. Owing to the lighting of the call lamp L II, the attention of the attendant in the alarm receiving station HBW will be drawn to the calling alarm call. Owing to the closing of the contact 4p, an excitation 30 circuit will be closed for the current impulse receiving relay J of the alarm receiving station HBW:—earth, rest contact 1a, choking coils Dr, a and b arm of the call seeker AS, a and b conductors of the connection line, choking coils Dr, relay J, working contact 4p, battery, earth. The alarm receiving station HBW is now prepared to receive the first 35 series of current impulses.

The alarm sender at the alarm giving station AGSt 431 dials now, for instance by 40 means of his number disc, the digit 4. The relay A at the distributing station VSt 1 follows the current impulse thus produced, and by means of the contact 1a, these current 45 impulses are transmitted along the path described above, to the relay J of the alarm receiving station HBW. As soon as the relay J becomes operative an excitation circuit will be closed for the relay K1 which is built 50 as a retardation relay and therefore remains excited during the whole series of current impulses:—earth, relay K1, working contact 21i, battery, earth. Owing to the operation of the relay K1, the contact 20k1 will be 55 opened, and the relays V1, V2 and V3 prevented from becoming operative.

Through the contact 7i, the four current impulses of the first current impulse series will be transmitted to the rotary magnet D1 60 of the selector W1:—earth, rotary magnet D1, rest contact 8v1, current impulse contact 7i, battery, earth.

The selector will be thereby turned to the extent of four steps. With its switch arm 65 w13, it prepares a circuit for the relays V1,

V2 and V3. After the termination of the first current impulse series (four current impulses), the relay K has its current cut off again, as the contact 21i permanently breaks its excitation circuit. Owing to the closing 70 of the rest contact 20k1, there will be closed therefore an excitation circuit for the relay V1:—earth, rest contact 20k1, rest contact 15v1, relay V1, rest contact 22f, selector arm w13 of the selector W1, battery, earth. By 75 turning over its contact 15v1, the relay V1 creates for itself a holding circuit independent of K1:—earth, working contact 15v1, relay V1, rest contact 22f, switch arm w13 of the selector W1, battery, earth.

At the same time the contact 28v1 is closed, owing to which an excitation circuit is closed for the relay R of a further alarm receiving station (FW1) connected in any desired manner (by means of the key WT1):—earth, relay R, signal line SL1, key WT1, rest contact 29v3, working contact 28v1, battery, earth.

The purpose of the keys WT1 and WT2, which are located in the central receiving station HBW, is to enable an operator in the central receiving station to selectively determine to which district receiving station a preliminary alarm signal will be sent. That is, a fire company located at FW1 might already be out fighting a fire and in that event the preliminary alarm signal coming over the circuit which includes key 28v1 could be transferred by the operator to a near district receiving station FW2. Thus both stations FW1 and FW2 are necessarily connected to the same alarm contact 28v1. The relay R, by closing its contact 30r, produces the switching in of the preliminary alarm hooter AH. According to the invention, the attendant at the alarm receiving station FW1 has then his attention drawn by the preliminary alarm hooter AH to the fact that an alarm is coming in.

Simultaneously with the said processes, the contact 8v1 is changed over owing to the excitation of the relay V1. If the alarm sender at the alarm giving station AGSt 431 dials the digit 3 of his number, then the current impulse series produced thereby and constituted by three current impulses, will be transmitted therefore to the lifting magnet H of the selector W2:—earth, lifting magnet H, rest contact 9v2, working contact 8v1, current impulse contact 7i, battery, earth. During this second transmission of current impulses, the relay K1 will be again excited in the same manner as already described and in that way will be opened the contact 20k1, so that the relay V2 will not be able to become operative on the closing of the off-normal contact 18k. The selector W2 is raised by the second current impulse series (three current impulses) to its third decade.

After the termination of the second current impulse series, current will be again cut off 130

from the relay K which will close its rest contact 20*k*1, whereupon the relay V2 will be excited:—earth, rest contact 20*k*1, rest contact 16*v*2, off-normal contact 18*k*, relay V2, 5 rest contact 22*f*, switch arm *w*13, of the selector W1, battery, earth. During the lifting of the selector W2 to the given decade, the off-normal contact 18*v*2, a holding circuit independent of the contact 20*k*1, 10 will be produced for the relay V2. The contact 9*v*2, will be turned over, and the rotary magnet D2 of the selector W2 will be prepared for the reception of the third series of current 15 impulses.

When the alarm sender in the alarm giving station AGSt 431 dials now the third and last digit of his number (the digit 1), this current impulse will be transmitted to the 20 rotary magnet D2 of the selector W2 which is of the well known Strowger vertical and rotary type as shown in United States Patent No. 672,942, along the following path:—earth, rotary magnet D2, rest contact 10*v*3, 25 working contact 9*v*2, working contact 8*v*1, current impulse contact 7*i*, battery, earth. The switch arms (in the drawing are shown only the switch arms *w*21, *w*22) of the selector W2 are advanced to one step in the given 30 decade (3rd decade), in accordance with the current impulse. During the turning of the selector the spindle contact 19*w* is closed in any desired mechanical manner.

When after the termination of the third 35 series of current impulses, current is cut off from the relay K1 which had again become operative during the current impulse sending owing to the closing of the contact 21*i* an excitation circuit will be closed for the 40 relay V3:—earth, rest contact 20*k*1, rest contact 17*v*3, spindle contact 19*w*, relay V3, rest contact 22*f*, switch arm *w*13 of the selector W1, battery, earth.

Owing to the changing or turning over of 45 the contact 17*v*3, a holding circuit independent of K1, will be closed for the relay V3.

As soon as the relay V3 becomes operative, it opens its contact 29*v*3 and thus 50 switches off the preliminary alarm to the further alarm receiving stations (FW1, FW2). At the same time is closed the contact 13*v*3, and the lamp L III switched in. Owing to the lighting of the lamp L III, 55 the attendant at the alarm receiving station HBW is notified that the alarm sending by the alarm giving station AGSt 431 (number selection) is finished. Owing to the changing over of the contact 10*v*3, the rotary magnet D2 of the selector W2 is cut out, and 60 the relay K2 excited:—earth, relay K2, working contact 10*v*3, working contact 9*v*2, working contact 8*v*1, current impulse contact 7*i*, battery, earth. With its contact 11*k*2, 65 the relay K2 brings about the switching in of the lamp L I:—earth, working contact

11*k*2, lamp L I, battery, earth. The lighting of the lamp L I indicates to the attendant at the alarm receiving station HBW that the person who gave the alarm has malevolently abandoned the alarm giving station AGSt 70 431 after giving the alarm (that is, after completing the number selection).

The attendant at the alarm receiving station HBW switches then his enquiry apparatus ABA into the connection line *a* *b*. The 75 arrangement of connections for the enquiry apparatus ABA is not shown in the drawing, as the connections in question are immaterial to the present invention. If the alarm sender still remains at the alarm giving station AGSt 431, the attendant of the alarm receiving station HBW asks for fuller particulars about the alarm in question (for instance the magnitude and kind of the fire). N is the telephone apparatus of the alarm 80 giving station AGSt 431.

When the enquiry instrument ABA is switched into the connection line *a* *b*, an excitation circuit will be closed for the relay L:—earth, plug, key, relay L, battery, earth. 90 The relay L closes its contacts 23*l*, 24*l* and 25*l* and switches in the lamps H4, Z3, E1, in the lamp field, which correspond to the calling alarm giving station AGSt 431. The selector W2, which, as stated, is of the 95 Strowger type shown in United States Patent 672,942, is constructed in such a manner that its switch arm *w*21 passes over banks of contacts which are interlinked or connected together in the direction of rotation 100 of the selector, whilst the switch arm *w*22 passes over banks of contacts which are interlinked in the direction of lifting of the selector. This ensures that a lamp field of 105 3 × 10 lamps will be able to indicate without ambiguity a range of 1000 numbers. The arrows in the drawing indicate in the well known manner the multiple switching of the lamp field. The attendant at the alarm receiving station HBW sends them in any 110 desired manner, for instance by number selection, which is described in our British Patent No. 270,755, the number received—in our example 431—to the next alarm receiving station, for instance FW1 or FW2.

After the alarm has been sent on to the next alarm receiving station (FW1, FW2), the attendant depresses the key AT. In that way the relay F is energized:—earth, relay F, switch arm *w*12 of the selector W1, release key AT, battery, earth. The relay F is connected to the 5th contact of the contact bank of the selector W1. The switch arms *w*11, *w*12, *w*13 and *w*14 were set to the fifth contact of the contact bank, by the sending 120 of the first current impulse series consisting of four current impulses. The relay F closes for itself, by means of its contact 26*f*, a holding circuit. By means of its contact 27*f*, 125 it brings the automatically acting interrupter 130

UB against the rotary magnet D1 of the selector W1 through the switch arm $w11$. In that way the selector W1 is turned back to its position of rest. By opening the contact 5 22f, the excitation circuits for the relays V1, V2 and V3 are opened, and by the opening of the contact 3f, the constant circuit for the test relay P is cut. The rest contact 5p closes therefore an excitation circuit for the release magnet M of the selector W2:—earth, rest contact 5p, release magnet M, off-normal contact 6k, battery, earth. The release magnet M produces then in any desired mechanical manner the release of the selector W2, 10 whereupon the installation is again in the position of rest.

Having now particularly described and ascertained the nature of our said invention and in what manner the same is to be performed, we declare that what we claim is:—

1. An alarm circuit system comprising alarm transmitting stations divided into districts, a central alarm receiving station, district alarm receiving stations, means at each 25 alarm transmitting station for transmitting to the central station a code of impulses consisting of a plurality of parts characteristic of the particular alarm transmitting station and district in which said station is located, 30 a part of said code impulses characterizing the district in which the alarm transmitting station is located, the other parts of said code impulses following in sequence the said first mentioned part of the code impulses and 35 completing the characterization of the particular alarm transmitting station, means at the central station for transmitting the alarms received from the transmitting stations to the district stations, and means operated 40 by the part of the code impulses characterizing the district in which the particular alarm transmitting station is located for sending a preliminary signal to a selected district station assigned to said alarm transmitting station.

2. An alarm circuit system comprising alarm transmitting stations divided into districts, a central alarm receiving station, district alarm receiving stations, means at each 50 alarm transmitting station for transmitting to the central station a code of impulses consisting of a plurality of parts characteristic of the particular alarm transmitting station and district in which said station is located, 55 a part of said code impulses characterizing the district in which the alarm transmitting station is located, the other parts of said code impulses following in sequence the said first mentioned part of the code impulses and completing 60 the characterization of the particular alarm transmitting station, means at the central station for transmitting the alarms received from the transmitting station to the district stations, means operated by the part 65 of the code impulses characterizing the dis-

trict in which the particular alarm transmitting station is located for sending a preliminary signal to a selected district station assigned to said alarm transmitting station and means for discontinuing said preliminary alarm on the receipt of the said other parts of the code impulses.

In testimony whereof we affix our signatures.
